NOVEL DETERGENT COMPOSITIONS

Edwin B. Michaels, Stamford, and Clayton A. Wetmore, Norwalk, Conn., assignors to Stamford Chemical Industries, Inc., Cincinnati, Ohio, a corporation of Ohio
No Drawing. Filed July 26, 1963, Ser. No. 297,974

10 Claims. (Cl. 252—152)

This invention is concerned with novel detergent compositions. More specifically, it relates to a detergent composition adapted for incorporation into a non-polar organic dry-cleaning solvent comprising alkali metal and/or alkaline-earth metal mahogany sulfonates and certain monoalkanolamine salts of alkyl arylsulfonic acids.

Mahogany sulfonates have been employed to improve dry-cleaning solvents. Improved detergency and soil dispersion properties of the latter solvents have been observed. Unfortunately, such additives impart to the dry-cleaning solvent relatively poor water solubilizing properties. Possession of water solubilizing characteristics of detergent additives is of significant consequence, for otherwise the presence of excess water in the solvent-detergent system can damage irreparably a garment to be treated. If the detergent additive could be modified so as to impart water-binding properties to an otherwise good detergent without impairing the latter's effectiveness, such a product would be highly desirable.

It is an object of this invention to provide a detergent additive composition which exhibits both enhanced detergency and water solubilizing or water-binding properties. It is a further object of the invention to provide an improved mahogany sulfonate additive to drycleaning solvents. Other objects and advantages will become apparent from the following detailed description.

It has been found that the stated objectives can be achieved readily by incorporating into a non-polar, organic drycleaning solvent a mixture of a monoalkanol amine salt of an alkylaryl sulfonic acid and either an alkali metal salt of a mahogany sulfonate or alkaline earth salt of a mahogany sulfonate having a molecular weight of at least about 425. It is surprising to find that mixtures as prepared hereinbelow specified exhibit both enhanced detergency and water binding properties.

According to the invention, neutralization of an alkylaryl sulfonic acid with an alkanol amine is performed in the presence of the alkali metal salt of an oil soluble mahogany sulfonic acid or mixtures thereof. Unexpectedly, it has been further found that the desired enhanced detergency is realized when the neutralization of the alkylaryl sulfonic acid by means of the amine is carried out in the presence of the mahogany sulfonate.

A good practice is to incorporate about 1 part of alkali metal or alkaline earth metal mahogany sulfonate in about 0.5 part to about 1.5 part, on a weight basis, of the aforementioned amine salt, and about equal parts of each of the sulfonate and the amine salt are preferred.

In general, any commercially available oil-soluble mahogany sulfonate having an average molecular weight of at least 425 can be employed herein. It is advantageous to employ an alkali metal salt of mahogany sulfonic acid, such as the sodium, potassium or lithium salt, although the alkaline earth metal salt, such as the calcium or barium salt, may also be utilized herein. Mixtures of alkali metal and alkaline earth metals are contemplated.

The higher alkylaryl sulfonic acid to be amine-neutralized can be widely varied. Among the sulfonic acid contemplated herein are, for instance:

octyl benzene sulfonic acid,
nonyl benzene sulfonic acid,
decyl benzene sulfonic acid,
undecyl benzene sulfonic acid,

2

dodecyl benzene sulfonic acid,
lauryl benzene sulfonic acid,
tridecyl benzene sulfonic acid,
myristyl benzene sulfonic acid,
5 hexadecyl benzene sulfonic acid,
octadecyl benzene sulfonic acid,
1-dodecyl naphthylsulfonic acid, and
β-myristyl naphthylsulfonic acid.

10 Exemplary monoalkanol amines utilized in the neutralization of the alkyl aryl sulfonic acid are the following monohydroxy lower alkyl amines:

Mono-ethanol amine,
Mono-n-propanol amine,
15 Mono-isopropanol amine,
Mono-n-butanol amine,
Mono-isobutanol amine, and
Mono-pentanol amine.

20 The detergent compositions, prepared by admixing the alkylaryl sulfonic acid with the mahogany sulfonate salt and the mixture neutralized with the appropriate monoalkanol amine, can be incorporated into a non-polar solvent, such as Stoddard's solvent, petroleum ether, deodorized kerosene, and mineral spirits.

25 As previously stated, it is a critically important aspect of this invention to effect neutralization of the alkyl aryl sulfonic acid with the aforementioned amine in the presence of the mahogany sulfonate salt. In general, the amine is added to a mixture of the alkyl aryl sulfonic acid and the salt of the mahogany sulfonate until a pH between 6.5 and 9.5 is obtained, and preferably between 7.0 and 8.5. At this point, an amber colored, viscous stable solution is noted. To reduce the viscosity of the resultant solution so that it can be handled with greater facility, it is a good practice to add, while preparing the solution and prior to neutralization, a small amount usually up to 25% of an inert organic solvent into the mixture. Such inert solvents are for instance:

30 Stoddard's solvent,
perchloroethylene,
deodorized kerosene,
mineral spirits, and
mineral oil,

35 45 To further illustrate the invention, the following examples of the preferred practice are presented. These are not to be taken as limitative of the invention. Unless otherwise stated, the parts are by weight.

50 *Example 1*

To a suitable reaction vessel are admixed 44 parts of sodium mahogany sulfonate, 56 parts of mineral oil and 44 parts of dodecyl benzene sulfonic acid. To the mixture is next added 12 parts of mono-isopropanolamine. Resultant mixture obtained is found to have a pH equal to 7.5.

55 *Example 2*

60 Into an appropriate reaction vessel are added 22 parts of calcium mahogany sulfonate, 56 parts of deodorized kerosene and 44 parts of dodecylbenzenesulfonic acid. The mixture is then admixed. Twelve (12) parts of mono-isopropanol amine are then added and gently stirred. A 65 terminal pH of 7.8 is obtained.

Example 3

70 To 22 parts of sodium mahogany sulfonate, 22 parts of calcium mahogany sulfonate and 44 parts of dodecylbenzenesulfonic acid in 56 parts of petroleum ether are added while stirring 12 parts of monoisopropanol amine. The mixture is then found to possess a pH of about 8.

3
Example 4

A mixture of 22 parts of sodium mahogany sulfonate and 22 parts of calcium mahogany sulfonate, 40 parts

swatch soiled with milk) and solvent relative humidity data as measured by conductivity measurements are presented in Table I below.

TABLE I

Ex.	Detergent in Stoddard Solvent	Percent Detergency		Percent Redeposition		Percent Water Soluble Stain Removal	Solvent R.H.
		Cotton	Wool	Cotton	Wool		
5.....	Oil-soluble sodium mahogany sulfonate of average M.W. of about 425.....	17.8	42.2	5.8	10.8	40	70
6.....	Ex. 1 detergent.....	33.5	56	2.1	11.0	100	65
7.....	Ex. 2 detergent.....	37	68	1.05	6.5	100	70
8.....	Ex. 3 detergent.....	41	68	2.1	6.5	100	65
9.....	Ex. 4 detergent.....	30.3	68	2.1	5.5	100	70
10.....	Monoisopropanol amine salt of dodecylbenzene sulfonic acid.....	27.3	41	8.4	19.8	85	65

of tridecylbenzenesulfonic acid in 56 parts of petroleum ether is added to an appropriate reaction vessel. Thereafter, 9.5 parts of monoisopropanol amine are added while stirring to the mixture, whereby a pH of 7.6 is obtained.

Although in each example above monoisopropanol amine is employed, other aforementioned monoalkanolamines can be substituted to obtain similarly improved detergents.

Enhanced detergency properties of the compositions illustrated in the table below are determined in the conventional manner involving the use of a launderometer as described in the AATCC Yearbook for 1955 at page 55. In a typical run, a standard soiled swatch and stainless steel balls together with a non-polar drycleaning solvent, containing 1% by weight of the detergent additive mixture as prepared by each of the above examples are added to a launderometer jar. After a twenty minute wash cycle, the washed swatch is removed from the jar, and dried to remove the solvent. Reflectance readings before and after washing of the soiled and unsoiled swatches are taken and recorded in percent detergency and percent redeposition, respectively. In the illustrative examples below, the initial reflectance readings of the cotton and wool swatches used are: 103 and 93, respectively. Percent detergency is determined by subtracting the reflectance reading of the soiled swatch and dividing this difference by the difference between the initial unsoiled swatch reflectance reading and soiled reflectance reading, multiplied by 100. Thus, for instance, the percent detergency for cotton is:

$$\frac{R - 30 \times 100}{96 - 30}$$

where R is the reflectance reading of the soiled swatch after drycleaning. The redeposition value in percent for cotton is similarly represented by the formula:

$$\frac{96 - R' \times 100}{96}$$

where R' is the reflectance reading of unsoiled swatches after drycleaning. In the examples below the percent detergency and percent redeposition are determined in perchloroethylene solvent.

Water binding test procedure is conducted in each of the examples tabulated below as follows:

A visual water tolerance value (V.W.T.V.) of an oil soluble detergent is a measurement of the amount of water that the detergent will hold or otherwise dissolve in solvent, such as perchloroethylene. Water tolerance value herein is obtained by visual measurements in the formula below by adding water to a known amount of detergent dissolved in solvent until the solution shows a definite cloudiness:

$$\begin{aligned} V.W.T.V. = & \frac{\text{amt. of water (in grams)}}{\text{amt. of detergent solvent sol'n. (in cc.)} \times \text{percent detergent}} \end{aligned}$$

The detergency results as well as water-soluble stain removal (determined by visual observation of a wool

swatch soiled with milk) and solvent relative humidity data as measured by conductivity measurements are presented in Table I below.

From Table I above, it can be readily seen that overall detergency values of the mixture is generally higher than the detergency values for the individual components. Advantageously, the compositions of the present invention exhibit synergistic properties with respect to sweet-stain removal.

In Table II below the visual water tolerance values are summarized.

TABLE II

Example	Detergent	Visual Water Tolerance Value
Ex. 11.....	Sodium Mahogany Sulfonate.....	0.67
Ex. 12.....	Example 1 Composition in Stoddard Solvent.....	1.6
Ex. 13.....	Example 2 Composition in Stoddard Solvent.....	1.2
Ex. 14.....	Example 3 composition in Stoddard Solvent.....	1.3
Ex. 15.....	Example 4 Composition in Stoddard Solvent.....	1.7

It will be seen from the above table that the compositions of the present invention exhibit a markedly higher water binding effect than do the mahogany sulfonates. This property is related directly to the maintenance of a low or safe solvent relative humidity.

We claim:

1. A non-polar solvent compatible detergent composition consisting essentially of:
  - 1 part by weight of a salt of an oil-soluble mahogany sulfonate having a molecular weight of at least about 425, said salt being selected from the group consisting of alkali metal, alkaline earth metal and mixtures thereof, and
  - from 0.5 part to 1.5 parts of monohydroxy lower alkyl amine salt of a higher alkyl aryl sulfonic acid, said amine salt being formed by reacting said monohydroxy lower alkyl amine with said higher alkyl aryl sulfonic acid in the presence of said mahogany sulfonate, and said mixture being substantially neutralized to a pH of from about 6.5 to 9.5.
2. A non-polar solvent compatible detergent composition consisting essentially of:
  - 1 part of a salt of an oil-soluble mahogany sulfonate having a molecular weight of at least about 425, said salt being selected from the group consisting of alkali metal, alkaline earth metal and mixtures thereof, and
  - 1 part of monohydroxy lower alkyl amine salt of a higher alkyl aryl sulfonic acid, said amine salt being formed by reacting said monohydroxy lower alkyl amine with said higher alkyl aryl sulfonic acid in the presence of said mahogany sulfonate, and said mixture being substantially neutralized to a pH of from about 6.5 to 9.5.
3. The detergent composition according to claim 1 in which the mahogany sulfonate is the sodium salt and the monoalkanol amine salt is monoisopropanol amine salt of dodecylbenzenesulfonic acid.
4. The detergent composition according to claim 1 in which the mahogany sulfonate is the sodium salt and the

monoalkanol amine salt is monoisopropanol amine salt of tridecylbenzenesulfonic acid.

5. The detergent composition according to claim 1 in which the sulfonate is a mixture of calcium mahogany sulfonate and sodium mahogany sulfonate and the monoalkanol amine salt is monoisopropanol amine salt of dodecylbenzenesulfonic acid.

6. A process for preparing an oil-soluble, detergent composition which consists essentially in the steps of: admixing in the presence of a salt of an oil-soluble mahogany sulfonate having an average molecular weight of at least 425, said salt being selected from the group consisting of alkali metal, alkaline earth metal and mixtures thereof, (a) a higher alkyl aryl sulfonic acid and (b) monohydroxy lower alkyl until a pH between about 6.5 and 9.5 is obtained, the mahogany sulfonate and the components (a) and (b) forming the amine salt being in proportion to provide from 0.5 to 1.5 parts of amine salt per part of mahogany sulfonate.

7. The process according to claim 6 in which the salt of the mahogany sulfonate is sodium mahogany sulfonate, the monoalkanol amine is monoisopropanol amine and the aryl sulfonic acid is dodecylbenzenesulfonic acid.

8. The process according to claim 6 in which the salt of the mahogany sulfonate is a mixture of calcium ma-

hogany sulfonate and sodium mahogany sulfonate, the amine is monoisopropanol amine, and the aryl sulfonic acid is dodecylbenzenesulfonic acid.

9. The process according to claim 6 in which the salt of the mahogany sulfonate is sodium mahogany sulfonate, the amine is monoisopropanol amine, and the aryl sulfonic acid is tridecylbenzenesulfonic acid.

10. The process according to claim 6 in which the salt of the mahogany sulfonate is potassium mahogany sulfonate, the amine is monoisopropanol amine, and the aryl sulfonic acid is myristylbenzenesulfonic acid.
